STRUCTURAL ELEMENT

Karl Kieser, Zollikon, Switzerland

Application June 14, 1939, Serial No. 279,221
In Germany June 16, 1937

8 Claims. (Cl. 72—61)

This invention relates to structural elements of coffered, box-like, or cellular construction, that is, formed with open-mouthed box like recesses or spaces which are closed by assembling a plurality of the elements in contact with each other and with opposing coffers or cells in register, the closed spaces thus formed being filled with concrete or cement to unite the elements.

An object of the invention is to provide coffered structural elements applicable to a wide range of constructions.

Another object of the invention is to provide such elements with coffers of standardised form enabling the elements to be assembled in transverse as well as in parallel relation.

The structural elements according to the invention are of substantially rectangular cross section, of width exceeding the depth, and coffers or cells may be provided in both of the narrow sides of the element corresponding to the depth dimension. One of the wider sides of the element may be continuous and flat while the other side presents the openings of the middle or main coffers of the element.

The coffers are separated by ribs which may have thin portions formed in them to facilitate the breaking through of openings for the passage of reinforcing members and pouring of cement.

The drawing shows a perspective view of a structural element.

The structural element is a box girder with middle and side coffers or cellular spaces.

The flat thin web which forms the base of the middle box like compartments or coffers 1 and the level under surface of the structural element is marked 19. Each of the sides 5 of the structural element has upper and lower flanges 2 and 3 in which are embedded longitudinal reinforcing irons 20, said flanges equally being connected by a web portion 11. The inner surfaces of the sides 5 of the middle coffers are inclined inwardly and downwardly.

The web portions 11 separate the middle coffers and the side coffers, ribs 12 are provided between the middle coffers and ribs 13 between the side coffers. Ridges 14 extend outwardly from the longitudinal flanges 2 and 3 to form the upper and lower boundaries of the side coffers, and the spacing ribs 13 extend across from the upper to the lower ridges. The outer surfaces of the ribs 13 and ridges 14 lie in one and the same plane.

Rectangular recesses 12 are provided in the ribs 12 between the middle coffers indicated by 9, and recesses 10 between the middle and side coffers. The walls 7 of the ribs 12 are arranged

slightly and equally inclined to one another and complete the boundary of the middle coffers, which for the rest are dome-shaped.

The breadth of the structural element is indicated by b, the height of the element by h, the pitch of the ribs 13 by a.

I claim as my invention:

1. A structural element in the form of a box girder of substantially rectangular form in cross section the width being greater than the depth, said element comprising side portions, a bottom portion connecting said side walls, a plurality of uniformly spaced webs extending transversely from one side portion of the element to the other 15 side portion to form a series of middle coffers, in said element, external ridges extending longitudinally along at least one of said side portions at the top and bottom thereof and forming a longitudinal channel in said side portion and a 20 plurality of uniformly spaced ribs extending across said side portion from ridge to ridge and dividing said channel into side coffers.

2. A structural element according to claim 1, in which the base surface of the bottom portion 25 is planar.

3. Structural element consisting of a box-girder like structure of greater width than depth with middle coffers in one broad side, and side coffers in both narrow sides of the element, said 30 side coffers and middle coffers being of equal dimensions measured longitudinally of the element.

4. Structural element according to claim 3 in which each middle coffer has two opposite inner 35 walls substantially planar and with an equal and opposite inclination to one another.

5. A structural element according to claim 1 in which the base surface of the bottom portion is planar and the edges of the ridges and ribs 40 defining the coffers in a side portion lie in one and the same plane at right angles to said base surface.

6. A structural element according to claim 1, in which recesses are formed in the webs between 45 the middle coffers where said webs join the bottom portion, to facilitate breaking openings in said webs.

7. A structural element according to claim 1, in which the ribs and webs defining the middle 50 and side coffers are made thin and easily destruc-

8. A structural element according to claim 3 in which the side coffers are symmetrical with respect to the median plane parallel to the broad 55 sides of the structure.

KARL KIESER.
